UNITED STATES PATENT OFFICE.

CHARLES W. SPONSEL, OF HARTFORD, CONNECTICUT, ASSIGNOR, BY DIRECT AND MESNE ASSIGNMENTS, TO THE AJAX UNIVERSAL JOINT COMPANY, OF HARTFORD, CONNECTICUT, A CORPORATION OF CONNECTICUT.

UNIVERSAL JOINT.

1,131,144.

Specification of Letters Patent. Patented Dec. 15, 1914.

Application filed August 12, 1914. Serial No. 856,835.

To all whom it may concern:

Be it known that I, CHARLES W. SPONSEL, a citizen of the United States, residing at Hartford, in the county of Hartford and State of Connecticut, have invented certain new and useful Improvements in Universal Joints, of which the following is a specification.

This invention relates to universal joints, among the principal objects of the invention being the provision of an article of this character which is exceedingly simple in construction, the parts of which can be readily and easily assembled, which possesses extreme strength and wherein the possibility of the joint being broken down by stresses and strains in action, is practically eliminated.

The invention possesses other features of novelty and advantage, which with the foregoing will be stated at length in the following description, wherein I will set forth in detail that one of the several convenient forms of embodiment of the invention, which I have selected for illustration in the drawings accompanying and forming part of the present specification, this showing being provided to enable those skilled in the art to practice the invention. It will be obvious that I do not limit myself to such disclosure; I may depart therefrom in radical respects within the scope of the invention defined by the claims following said description.

Referring to said drawings: Figure 1 is a perspective view of a universal-joint involving my invention. Fig. 2 is an elevation of the joint. Fig. 3 is a similar view as seen either from the right or left in Fig. 2. Fig. 4 is a detail view in perspective of a stud. Fig. 5 is a longitudinal sectional view of one of the shafts and its adjuncts, the other shaft for sake of clearness being omitted. Fig. 6 is a detail view in perspective, of a coupling member, and Fig. 7 is a detail view of one of the sections of the coupling member.

Like characters refer to like parts throughout the several views.

The joint involves in its make-up two forked members such as those respectively denoted in a general way by 2 and 3, and which as represented are socketed to receive the reduced ends of the shafts 1 pinned

or otherwise suitably secured to the respective forked members. The bifurcated members as shown are of duplicate and respectively integral construction, their forks in the present case, being situated at right angles to each other and being interfitting but separated sufficiently to allow for the maximum universal movement.

In the present case the two members 2 and 3 are united for relative universal movement, by a suitable coupling member such as the block denoted in a general way by 5 and by studs each denoted in a general way by 6 and each preferably in one piece, there being four of such studs which are alike in construction, so that a detailed description (hereinafter given) of one stud will apply to the others. The coupling member or block 5 consists as represented, of duplicate sections 7 and 8 of annular form, and when I speak of them as being "annular" I do not mean to imply that they are circular, for as illustrated they are rectangular in shape, and as having flat faces fitting solidly and substantially against each other and being maintained in this relation by suitable means such as by the tie or clamping bolt 9. The abutting surfaces of the sections 7 and 8 have semi-circular apertures or notches 10 which mate to produce two pairs of circular bearing-holes to receive the pivot or journal portions of the respective studs 6, the bearing holes of the respective pairs being in the present case, diametrically opposite. The coupling member or block 5 is in no sense chambered but is open from end to end to present an unobstructed passage which is somewhat larger than the body of the connecting bolt 9 to provide for the ready movement of said bolt through said passage and also as an oil-reservoir when properly closed.

The head of the bolt 9 and the nut 9 thereof have cylindrical reduced portions to fit within the coupling block 5 when the bolt is set. By reducing the head and nut of the bolt flat shoulders are produced on the inner side of said head and nut which fit closely against the upper and lower sides of the coupling block to prevent accidental escape of the lubricant of whatever character it may be (oil being generally provided for this purpose) from the interior of the coupling member.

Each stud 6 as illustrated comprises an outer retaining head 11, an inner retaining head 12, and an intermediate pivot or journal portion 13, the retaining head 12 being 5 of less diameter than the retaining head 11 and of the body 6' to permit the free passage of the respective studs through the perforations or holes 14 in the branches of the forks of the two members 2 and 3 from outside 10 the same. It should be noted that the studs 6 are not integral with the bifurcations of the members 2 and 3, so that the latter can be made of comparatively soft material, while the studs 6 and the coupling-block 5 15 can be hardened as may be required. The retaining heads 11 as shown fit counterbores in the outer ends of the holes 14, the bodies 6' of the studs being of a little less diameter than said heads 11 but of slightly greater 20 diameter than the pivot, journal or trunnion portions 13 and inner retaining heads 12. It will also be observed that the flat shoulder formed at the junction of the head 11 and body 6' of each stud 6 has a substantial 25 bearing engagement against the bottom of the counterbore in which said head 11 is disposed and that in like manner the inner head 12 of each stud has a firm, substantial bearing engagement against a flat surface of 30 and within the coupling block 5 confining the same.

The studs 6 are preferably driven into place and while they might under ordinary circumstances be securely held against rotation 35 by such a driving fit, I prefer to not altogether rely on this but to provide an additional safeguard for instance in the shape of a suitable key, to insure positively non-rotation of said studs. As shown the 40 members 2 and 3 have shallow holes 16 to facilitate the staking of stock from said members to enter the keyways 17 in the respective heads 11.

In assembling, the following procedure 45 may be adopted: Initially the four studs are driven into place and keyed as already described. The bolt 9 is then passed through the opening of the lower section 7 of the coupling block 5 after which said section with the bolt therein is introduced between the branches of the bifurcation of the forked member 2 with the section 7 and bolt 9 at right angles thereto, until the trunnions 13 of the diametrically opposite studs 50 6 are received within two diametrically opposite recesses or apertures 10 of said section 7, following which the latter with the bolt 9 therein is turned to bring the head of said bolt down until the axis of the bolt coincides 55 practically with the axis of the member 2. Succeeding this the upper section 8 is introduced between the branches of the member 3 and shifted therein until two diametrically opposite apertures 10 of said section 60 65 receive the journal portions 13 of the studs

6 of said member 3. The forks of the two members 2 and 3 are then interfitted at right angles to each other until the section 8 fits flatwise against the section 7, which brings the recesses 10 into register to form two 70 pairs of diametrically opposite bearing holes to receive the two pairs of studs 6. The member 3 if necessary is then moved approximately at right angles to the member 2, so that the nut 9' can be applied to 75 the bolt and then set.

I desire to call attention to the following facts, some of which have received brief allusion hereinbefore: The trunnion or coupling block and trunnion or pivot studs can 80 be hardened throughout to insure long life and adequate wear, without necessarily hardening the forked members. The organization is such that the parts can be quickly and easily separated and as readily 85 reassembled with the identical parts, none of which, it will be observed, need be riveted. The branches of the bifurcated members are securely locked together against outward or inward movement. The trunnion studs are alike and the same statement applies to the forked ends of the two shafts and also to the sections or halves of the trunnion or coupling block. The various 90 parts are interchangeable and merely by removing a bolt the elements of the joint can be at once separated. The joint possesses an unusual amount of strength. The annular trunnion block in view of its form, can be lapped on the inside, to correct any distortion due to hardening or otherwise, and when it is in operative position, provides ample space for holding a lubricant. A joint involving the invention can be used 95 with advantage in many different connections.

What I claim is:

1. A universal joint comprising forked members, the forks of which are interfitted and at approximately right angles to each other, a sectional coupling member situated within the forks, studs disposed in pairs at right angles to each other, the coupling member having bearing holes and the studs having trunnions to fit said bearing holes, 110 each stud having inner and outer retaining heads, the inner heads being confined within the coupling member and the branches of said forks having holes to receive said studs, the holes being sized to permit the passage 120 of the inner heads of the studs therethrough from the outside of the forks and the outer heads of the studs having a bearing engagement against the respective forks, and means for holding the sections of the coupling member together.

2. A universal joint comprising forked members, the forks of which are interfitted and at approximately right angles to each other, a sectional coupling member situated 130

within the forks, studs disposed in pairs at right angles to each other, the coupling member having bearing holes and the studs having trunnions to fit said bearing holes, each 5 stud having inner and outer retaining heads, the inner heads being confined within the coupling member and the branches of said forks having holes to receive said studs, the holes being sized to permit the passage of 10 the inner heads of the studs therethrough from the outside of the forks and the outer heads of the studs having a bearing engagement against the respective forks, the sections of the coupling member being open, 15 and a bolt extending through the openings of the sections of the coupling member, the head of the bolt having a bearing against the outer side of one coupling member section and the nut of the bolt having a bearing 20 against the outer side of the other coupling member section.

3. A universal joint comprising forked members, the forks of which are interfitted and at approximately right angles to each 25 other, a split coupling member within the forks, studs disposed in pairs at right angles to each other, the coupling member having bearing holes and the studs having trunnions to fit said bearing holes, each stud 30 having inner and outer retaining heads, the inner heads being confined within the coupling member, the branches of the forks having holes through which said studs are passed, the holes being sized to permit the 35 passage of the inner heads of the studs therethrough from the outside of the forks, said holes having counterbores at their outer ends in which the outer heads of the respective studs fit, and means for holding 40 the sections of the coupling member together.

4. A universal joint comprising forked members, the forks of which are interfitted and approximately at right angles to each 45 other, a split coupling member within the forks, studs disposed in pairs at right angles to each other, the coupling member having bearing holes and the studs having trunnions to fit said bearing holes, said studs 50 having inner and outer retaining heads, the inner heads being confined within the coupling member, and the branches of said forks having holes into which the studs are driven, the holes being sized to permit the 55 passage of said inner heads therethrough from the outside of the forks and the outer heads of the respective studs bearing against the branches of the respective forks, means for holding the sections of the coupling 60 member together, and means for keying the studs in place, against rotation.

5. A universal joint comprising forked members, the forks of which are interfitted and approximately at right angles to each other, a split coupling member within the 65 forks, studs disposed in pairs at right angles to each other, the coupling member having bearing holes and the stud having trunnions to fit said bearing holes, said studs having inner and outer retaining heads, the 70 inner heads being confined within the coupling member, and the branches of said forks having holes into which the studs are driven, the holes being sized to permit the passage of said inner heads therethrough 75 from the outside of the forks and the outer heads of the respective studs bearing against the branches of the respective forks, and means for holding the sections of the coupling member together, said outer heads 80 having keyways and the stock of the forked members being staked into the respective keyways to prevent rotation of the studs.

6. A universal joint comprising forked members, the forks of which are interfitted 85 and approximately at right angles to each other, a split coupling member, the sections of which abut, the abutting faces having recesses which register to form two pairs of diametrically opposite bearing holes, the 90 studs having portions to fit said bearing holes, each stud having inner and outer retaining heads, the inner heads being confined within the coupling member and bearing against the inner surface thereof, the 95 branches of the forks having holes to receive the studs, the holes being sized to permit the passage of the inner heads of the studs therethrough from outside the forks, and the outer heads having a bearing 100 against the forks, and means for holding the sections of the coupling member together.

7. A universal joint comprising a fork, a coupling member fitted in said fork, opposite studs pivotally-connecting the coupling 105 member and the fork, the branches of the fork having holes and the studs having inner and outer retaining heads, the inner retaining heads being situated within the coupling member and the holes being of a 110 size to permit the passage of the inner heads of the studs therethrough from outside said branches, a second fork, and means for pivotally connecting said coupling member with said second fork to permit relative 115 universal movement of the two forks.

In testimony whereof I affix my signature in presence of two witnesses.
